(57) **CLAIM**

The ornamental design for a vehicle front fascia, as shown and described.

DESCRIPTION

FIG. 1 is a perspective view of the vehicle front fascia;
 FIG. 2 is a front view thereof;
 FIG. 3 is a top plan view thereof; and,
 FIG. 4 is a left side elevation view thereof (where the right side elevation view is omitted since the right side elevation view is identical to the left side elevation view).
 The broken lines shown in the drawings depict portions of the vehicle front fascia that form no part of the claimed design.
